UNITED STATES PATENT OFFICE

FRANCO MAZZINI, OF MILAN, ITALY

STRUCTURE OF MONOPLANES WITH THICK WINGS

Application filed April 4, 1929, Serial No. 352,465, and in Italy April 13, 1928.

The present invention has reference to improvements in the structure of monoplanes fitted with non-supported wings and more especially in the structure of the wings, 5 the object of the said improvements consisting in simplifying their construction and also in diminishing the weight of the whole by giving the parts which bear the stresses, a shape which is better suited to the work 10 for which they are intended.

It is known that up to the present the monoplanes with nonsustained thick wings, viz: the monoplanes having overhanging wings without external supports, have been 15 constructed in the same way as biplanes, which are fitted with two longérons for each wing, while the structural requirements of the two types are different, in view of both the difference in the proportions between the thickness of the wing and its 20 depth, and also of the variability of the said thickness on each section, such thickness being greatest towards the centre of said section.

25 As the resistant or working structure must be inserted within the thickness of the wing and must have the minimum possible weight, it will be convenient to dispose it in such a way as to obtain the maximum rigidity 30 and resistance of the wing against all bending and torsional stresses to which it is subjected, taking advantage of the particular conditions in which it has to work.

According to the present invention the 35 above object is obtained by placing the sustaining or resistant structure in such a position as to allow of the maximum dimensions being assigned to it, and by building it in such a way as to enable it to resist, with the 40 minimum weight consistent with a given coefficient of safety, to all bending and torsional stresses of the wing.

Consequently, according to the present 45 invention, the construction with two or more longérons which has been adopted up to now to obtain a resistant structure in the thick wings, is replaced by a single central longeron, which is placed approximately along the line passing through the centres 50 of pressure of the wing, and which is rigid

and resistant in an almost uniform manner and on all the sides of its contour, both to bending and to torsional stresses.

On the accompanying drawing which 55 serves to schematically illustrate a practical embodiment of the longeron and its component parts:

Figs. 1 and 2 show respectively a vertical section through the wing and a plan view 60 of the same.

Fig. 3 is a perspective view of a portion 65 of the longeron alone.

Figs. 4 and 5 are cross sections of two 70 tubular forms of the runners of the longeron, which are made of sheet metal.

Fig. 6 is a cross section of one of the rods 75 of the trellis work.

Figs. 7 and 8 show in side elevation and in section the details of the connection of the runners with the rods of the trellis work 70 of the longeron.

Fig. 9 shows in elevation the arrangement of the trellis work on a side face of another embodiment of the longeron.

Figs. 10, 11, 12 and 13 show some types 75 of metallic profile elements which may be used for the construction of the said longeron.

In the drawing (Figs. 1 and 2) —a— denotes the longeron and —b— the ribs 80 which rest on it. In Fig. 1 the section of the longeron —a— is cross-hatched so as to differentiate its parts from those of the ribs —b— which are fastened to it.

As it is shown in the example of the drawing, the longeron is prismatic, has nearly a square section and is composed of four runners —c— which are disposed along the four edges of the prism, and are connected between them on all four faces by a trellis work formed 90 of strips —d— that are disposed four by four and converge in centres which are diagonally opposite, and are joined by diagonal rods —e— arranged inside the longeron (Fig. 3).

A three-dimensional net work is thus obtained, which is formed by four runners within which a trellis work is constructed which may be considered as being made up of a series of tetrahedric equilateral elements having, two by two, an adjoining edge in common. 95 100

A beam, constructed as described, and having its trellis work rods inclined at an angle of about 45° in relation to the runners, has the property to resist to torsional stresses with the minimum weight, because in such case the forces that are acting along the oblique rods of the trellis work, balance themselves, and the runners are subjected to practically no appreciable stress. Said stresses are completely eliminated when the said inclination of the rods is exactly 45° .

The four runners are therefore subjected to bending stresses only, while the trellis work is subjected to torsional and shearing stresses, which latter stresses are however absorbed by the torsional stress in the ordinary conditions of construction.

For the calculation of the torsional stresses the runners therefore may be considered as being removed, thus remaining a beam made up of a series of the aforesaid tetrahedric equilateral elements which resist torsional stresses.

Although the example of construction illustrated in the drawing refers to a prismatic beam having a square section, it will be understood that it would also be possible to use a prism having a polygonal section with any number of sides, but it is always advisable that this section should be a regular polygon, and consequently the runners be at equal intervals and disposed according to the generating lines of a circular cylindrical surface and that they should subsequently be trellised so as to constitute an undefeatable system.

In the particular case in which the section of the beam is a triangle, the construction of the beam is simplified as in this case there are no inner diagonals, the sole trellis work on the faces being sufficient to render the system undefeatable.

With the above said equality of the faces, the uniformity of resistance of the whole contour is obtained, upon which fact the construction according to the present invention is based.

The beam longérons consisting of steel or light alloys, such as duraluminium or electron, can have a tubular shape or can be formed with riveted sheet metal plates, in which case they have preferably a square section as shown in the example in Figs. 4 and 5.

In the first of these figures the runner is made with a simple angle iron —*f*— and with an angle —*h*— having edges —*k*— so bent as to allow of the riveted joints being made, both these angle irons having eventually one or more recesses —*i*—.

In Fig. 5 the runner is made with a simple angle iron —*f*— by two U section pieces —*m*— and by a cross section piece —*n*— which serves for riveting these two latter pieces between themselves. The angle piece —*f*— as well as the U section pieces —*m*—

may be provided with one or more recesses —*i*—.

Also the trellis work rods may be of a tubular shape or formed of riveted sheet metal plates, as shown for instance on Fig. 6, which refers to the case of a runner which is made up with two flat sheet metal plates —*p*— combined with two U section pieces —*m*—.

The method of jointing the runners and the trellis work rods constructed as above described is shown on Figs. 7 and 8, in which the parts corresponding to those shown on Figs. 4, 5 and 6 are indicated with the same reference letters.

As it is shown in these figures, the runner —*c*— is of the same type as the one shown in Fig. 4, the rods —*d*— of the trellis work are fixed to the internal angle iron —*h*— by means of the U boxes —*g*— which embrace them and to which they are riveted at the point —*r*—; the piece —*g*— is in turn fixed on the runner by means of the riveted joint —*s*—.

On each side of the axis of the juncture of the various elements diaphragms —*t*—, designed to stiffen the section, which are placed within the runners —*c*— and are attached by the bolts —*u*—.

The area of the resisting metallic section of the four runners of the longéron is made to gradually decrease from the joint towards the end, and this diminution is obtained by either tapering the angle irons, or by forming them with sheet metal plates superposed in decreasing number or lastly by composing them of a plurality of jointed stems of different thickness.

The type of longéron above described having oblique trellis work rods which converge in diametrically opposite junctures, does not constitute the only embodiment with which the present invention can be carried into practice, as the central longéron may also be formed of a trellis work built up with struts or posts —*v*— lying on planes which are normal to the axis, and with tie-rods and counter tie rods —*w*— arranged crosswise in each section, as shown by way of example on Fig. 9 which shows schematically one side of the longéron constructed in this manner, and in which the cross sections of the runners and of the struts may have the shapes shown in Figs. 4, 5 and 6.

The connections and other details of the trellis work are designed and made in accordance with the usual practice followed for the construction of metallic bridges.

For large aeroplanes, and when extra light metals are used, such as electron, it may also be possible to adopt open and thick angle sections (Figs. 10, 11, 12, 13) both for the runners and for the diagonal pieces, according to the technical practice followed in iron constructions.

The ribs are scarfed into the longéron and

transmit by flexion the forces deriving from the pressure and under-pressure of the air. In normal flying, as the longéron is situated in correspondence with the line of the centres of pressure, the bending stresses on the two sides balance one another, and in pitching flight a bending moment is transmitted to the longéron from the rear side, which is absorbed by the resistance to torsion of the longéron.

Having described my invention, what I claim is:—

1. A construction for thick wings on monoplanes comprising a single longéron in each wing, said longéron being composed of a plurality of tetrahedral elements to create torsional resistance in said longéron.

2. A longéron for thick wings of monoplanes comprising a plurality of members arranged to form tetrahedral elements, said tetrahedral elements having one edge in common to create torsional resistance in said longéron.

3. A longéron for thick wings of monoplanes comprising more than three runners arranged longitudinally in said wing and spaced at intervals corresponding to the vertices of regular polygons and a plurality of members connected between said runners and arranged in tetrahedrons to create rigidity, bending and torsional resistance in said longéron.

4. A longéron for thick wings of monoplanes comprising more than three runners arranged longitudinally in said wing and spaced at intervals corresponding to the vertices of regular polygons and a plurality of members connected between said runners and arranged in tetrahedrons, adjacent tetrahedrons having one face in common to create rigidity and bending resistance as well as torsional resistance in said longéron.

5. A longéron for thick wings of monoplanes comprising four runners arranged longitudinally in said wing and spaced at intervals corresponding to the edges of a rectangular prism, a plurality of rods in zig-zag position in each face of said prism and having alternate junctures meeting alternate junctures of rods in adjacent surfaces of the rectangular prism and diagonal rods connecting diagonally opposite junctures of said rods.

6. A longéron for thick wings of monoplanes comprising four runners arranged longitudinally in said wing and spaced at intervals corresponding to the edges of a square prism, a plurality of rods in zig-zag position in each face of said prism, making angles of 45° with said runners and having alternate junctures in common with alternate junctures of rods in adjacent surfaces of the square prism and diagonal rods connecting diagonally opposite junctures of said rods

and making angles of 45° with said surfaces of the square prism.

In testimony whereof I have affixed my signature this 18th day of March, 1929.

FRANCO MAZZINI.
